UNITED STATES PATENT OFFICE.

CHARLES S. WEEKS, OF SOUTH ORANGE, NEW JERSEY, ASSIGNOR, BY MESNE ASSIGNMENTS, TO THE GERRARD COMPANY, INC., OF SAN FRANCISCO, CALIFORNIA, A CORPORATION OF DELAWARE.

PACKAGE-BANDING MACHINE.

Original application filed September 13, 1923, Serial No. 662,464. Divided and this application filed May 15, 1924. Serial No. 713,418.

This invention is a tension means for package banding machines.

This application is a division of a prior application filed by me September 13, 1923, Serial No. 662,464, for a package banding machine.

In this invention a band, such as a wire, is applied under tension to a package, and a salient feature of said invention consists in holding or retaining said band under tension independently of the action of the tensioning means and during the subsequent operation or operations of securing or fastening the band while it remains under tension. This new step of holding or retaining the band under tension independently of the action of the tensioning means contributes to the performance of an additional function i. e. that of returning the operating member of the tensioning means to a normal position convenient to the operator for applying pressure to said operating member for the purpose of holding the machine steadily in place upon the package and in the required relation to the band during the aforesaid subsequent operations of fastening or securing said band.

My invention is characterized by a tensioning means of novel construction, wherein two members are operated conjointly for pulling the band in opposite directions at one and the same time, thus distributing the strain on the band, facilitating the take-up of slack in said band, and placing that amount of tension on said band required to compress or bind the package and to embed said band in the corners of said package, it being desirable in this art to so tightly apply the band as to preclude its dislodgment when shrinkage occurs in the relatively soft and inexpensive wood composing the box or case. In the preferred form, the tension means embodies a single shaft, a plurality of rockers or heads carried by said shaft around which the band is strained upon the rotation of the shaft in one direction, and means on said rockers or heads for the attachment or anchorage of the respective end portions of said band. The rockers or heads are positioned at the respective sides of a band-securing or fastening means, and they turn on an axis parallel to the throat or slot within which are trained or positioned

parallel parts of the band the major part of which passes around the package, as a result of which the turning movement of the shaft and said rockers pull on the end portions of the band in directions at a right angle to the looped part of said band, and, furthermore, said two rockers pull the end portions of said band in opposite directions at the same time. The shaft and rockers are turned by a suitable operating member in the form of a lever arm, adapted to be operated by hand in a manner to turn the rockers for an indefinite distance so that it is within the power and judgment of the operator to apply strain to the band until the required tension is applied thereto, at and subsequent to which stage in the process of applying tension to the band the latter is held or restrained from retrograde movement by the action of the hereinbefore mentioned holding or retaining means.

A further feature of the invention consists of a band-holding means especially designed for use in conjunction with a pre-formed and deformed wire adapted to serve as a package band, said means including a plurality of dogs, one of which is fixed relatively to the other, and the latter being pivoted and spring actuated for movement with respect to the fixed dog, whereby the dogs are adapted to be opened automatically to facilitate the introduction of the deformed band, and said dogs are adapted for engagement with shoulders of said deformed wire band for holding the latter effectively against slippage under the tension applied to said band. The described holding dogs are carried by one of the rockers or heads, and they are so positioned that the deformed end portion of the wire band is thrust easily into the holding device while the wire band (composed of a length of straightened wire) stands in a position outwardly from the machine, thus facilitating the operation of initially inserting the wire band and anchoring it by the co-operating dogs on one of the rockers or heads of said tension means.

Other functions and advantages of the invention will appear from the following description taken in connection with the drawings, wherein—

Figure 1 is a plan view of my tension

means in conjunction with a wire tying machine of my prior application.

Figure 2 is an elevation looking at the left side of the machine with the tension means in normal position to receive an end of the band.

Figure 3 is a view similar to Figure 2 with the tension means rotated a given distance for placing tension on the band.

10 Figures 4 and 5 are views looking at the right side of the machine with the tension means in the positions corresponding respectively to Figures 2 and 3.

Figure 6 is substantially a vertical section 15 on the line 6-6 of Figure 4.

Figure 7 is a horizontal section on the line 7-7 of Figure 6.

20 Figures 8 and 9 are perspective views of the tension means in different operative positions thereof.

Figures 10 and 11 are perspective views of the anchor blocks.

25 The machine frame A includes a base plate a and short posts b for a horizontal shaft B. Bearing plates e are secured to the base between the posts b, and these plates support a twister pinion C, operated by a gear segment O to which movement is imparted by an operating lever P. Slotted plates D E are fixedly attached to the machine frame, and with said plates co-operate the cutters Q R held in position by springs q' and adapted to be operated by the studs r, which are carried by the gear segment O.

30 35 At one side of the throat d, and at a suitable distance from it, a band-directing member F is provided on the bed plate a, either cast therewith or made in a separate piece, and attached thereto. This directing member is shown as having a curved face f in advance of a straight face f' with which 40 coacts a gripping face g on one of the band-holding dogs G. Said dog is positioned upon a part of the directing member F for 45 movement in a horizontal plane, the direction of said movement being toward or from the faces f f' of the directing member F. The dog is pivoted on a stud g' and normally said dog is impelled toward the 50 member F by a spring g, the latter being housed within a recess of the dog.

Another band-directing member H is provided on the bed plate, the same being positioned on the opposite side of the throat d 55 from the described member F. This member H is likewise provided with a curved face h and a straight face h' for contact with a part of the band, said member H being provided with an upstanding lug h² against 60 which is fitted a second holding dog I, the latter being in overhanging relation to a flat face of directing member H. This dog is mounted for movement in a vertical plane, the direction of said movement being toward 65 or from the flat horizontal face of the mem-

ber H, said dog being fitted for pivotal movement on a stud i fast with the lug h², and being actuated by a spring i' concealed within a recess of the dog.

The tension means for a wire band 70 includes the shaft B and a plurality of rockers or heads J, K, each rocker being provided with means for the attachment thereto of the wire band. A single shaft B is provided for carrying the two rockers or heads, said 75 shaft B being positioned horizontally and at a suitable elevation above the bed plate, rearwardly of the throat d in the machine frame.

The shaft is journaled for free rocking 80 movement in the bearings b' of the posts b, and the end portions of this shaft protrude beyond the bearings b', see Figure 4, for the reception of the rockers or heads. Each rocker or head is shown as a single casting, 85 with a sleeve j, an arcuate face j', a rib or flange k adjacent said arcuate face, and a lug k' for the accommodation of the band gripper. The sleeves j of the two rockers are fitted on the protruding ends of the shaft, 90 to which shaft the rockers are made fast in a suitable way as by the screws k². The rockers are positioned at opposite sides of the throat d, and the twister pinion C, and in a plane rearwardly of the same, said 95 rockers turning on an axis afforded by shaft B parallel to the length of the throat d. One of the rockers, as J, is provided with a socket l for the reception of a hand lever L provided with a grip l', whereby the lever 100 is arranged to be grasped conveniently by one hand of the operator so as to rotate shaft B and the two rockers.

As a means for attaching a binder to the rocker J, it is provided with a gripper, one 105 form of which is indicated at M. This gripper may be of any construction suitable for the purpose, and it may be constructed to hold a flat wire band, or a plain round wire, or a plain round wire band, or a band 110 of any form. Said gripper in one embodiment of the invention is adapted for receiving and holding a deformed end portion y (see Figure 7) of a preformed band Y, the latter being composed of a single piece of 115 straightened wire the length of which is suitable for passing around the case or box Y'. Said gripper, designated in its entirety by letter M, is carried by the lug k' of rocker J, and it comprises a fixed dog m and a 120 movable dog m', the two dogs being relatively inclined to produce a tapering space into which and through which the shouldered deformed end of the wire band is 125 adapted to be thrust so as to contact with said inclined faces and to automatically open the gripper M to the end that the mere act of thrusting the wire band into the gripper will result in the engagement of the 130 dogs with the shouldered and deformed wire

so as to lock said wire to the rocker J, and preclude any slipping of the wire relatively to the rocker when tension is applied to said wire band. The dog m of the band gripper 5 is shown as comprising a piece of hardened metal fixedly attached to the lug k' of the rocker. The other dog m' consists likewise of a piece of hardened metal, which is attached pivotally to the lug k' of rocker J 10 by a stud m^2 , and with the said pivoted dog coacts a spring m^3 , the tension of which presses the nose of dog m' toward and into contact with the nose of the fixed dog m . The two dogs composing the gripper M for 15 the deformed wire turn with the rocker J when a partial rotation is given thereto by the shaft B, and said gripper thus co-operates with the rocker in pulling the wire band around the arcuate face j' of said 20 rocker J, the wire band sliding freely against the faces of the directing member F and past the serrated face of the holding dog G, see Figure 7. Although the rocker J is shown and described as having a gripper M for a deformed wire, it is apparent 25 that said gripper may be used for the attachment of a plain wire or band to the rocker, and, further, that the gripper may be modified and altered so as to be useful in 30 fixedly attaching any kind of band or wire to the rocker.

The other rocker K is provided on its lug k with suitable means for the attachment of one end portion of the wire or band, said 35 attaching means being shown as one or a plurality of studs n fixed to the lug k' and around which the end portion of the wire is adapted to be looped. See Figure 5. The end portion of the wire Y is thus adapted 40 to be fastened fixedly to the rocker K, so that on the rotation thereof the wire is pulled into contact with the arcuate face j' of said rocker K, the wire sliding freely with reference to the guiding faces of plate 45 H and slipping past the serrated gripping face of the holding dog I, see Figure 5.

The operation is as follows: The machine is placed upon a case or box Y' adjacent the position to be occupied by the wire band to 50 be applied thereto, the two levers L P lying rearwardly of the twister, see Figures 1, 2 and 3. A piece of straightened wire of the proper length to pass around the package, and preferably a wire Y with a deformed 55 end y , is selected, and said deformed end portion is thrust between the guiding faces of directing member F and dog G until said deformed end passes between the dogs m m' of the gripper M carried by the 60 rocker J, whereupon the wire is pulled forwardly until the shoulders of said wire are engaged by said dogs, for which forward movement of the wire it is necessary for the operator to release the dog G from contact 65 with the wire by pressing on the upstanding finger piece g^2 provided on said dog G. At the preliminary manipulation of the wire band, it extends in a straight condition outwardly from the machine, and it is easily inserted between the members F G for locking engagement with the gripper M, it being noted that the rocker J in the idle position thereof presents the gripper M into the path of the shouldered wire and that the parts F G act to direct the wire in a path 70 which insures the introduction of said shouldered part of the wire into the gripper M, the engagement of the gripper dogs m m' with the shoulders of the wire being semi-automatic. 75

The wire having been inserted and held by the gripper in the rocker J, the operator next proceeds to bend said wire around the curved face f of the directing member F, and to pass the wire below the knife Q, through 80 the slot in plate D, into the throat d of the machine and the slot in the twister pinion C, and the slot of plate E and below the knife R. The wire is now passed around the package to produce the loop shown in Figures 1, 85 7, 8, 9 and 10, and to position two parts, y' y^2 , of said wire into parallel relation, the part y^2 being arranged to pass through the slots of plates D, E, the slot of the twister pinion, and below the knives Q, R, where- 90 upon said wire part y^2 is bent around the curved face of the directing member H, passed below the other holding dog I, and bent upwardly around the holding stud n of the rocker K. The respective parts y' y^2 95 of the wire band are thus held by the gripper M and the stud n into fixed relation to the rockers, J, K, of the tension mechanism, with the parallel parts y' y^2 in the slotted plates and the twister. The operator now 100 grasps the two levers L P with his hands, and applies pressure with one hand on lever P to hold the machine steadily in place while he pulls upwardly and forwardly with the other hand on lever L, the effect of which 105 is to turn the shaft B and the rockers J K to an extent determined by the operator for applying the tension required to the wire loop, the operations of tensioning the wire being depicted clearly in Figure 8. It will 110

be noted that the respective ends of the parallel parts y' y^2 of the wire loop extend around the directing members F H at substantially a right angle to the plane of the loop, and that these ends of the respective 115 parallel parts y' y^2 are pulled by the rotative motion of the rockers in a direction at right angles to the plane of the loop, one rocker J pulling on the wire in one direction 120 lengthwise of the loop, whereas the rocker K pulls on the wire in the other direction lengthwise of the loop, see Figure 8, the effect of which is to strain the wire equally 125 by pulling in two directions, thereby taking up the slack and placing tension on the wire 130

by an expeditious operation. During the pull on the wire, the dogs G I turn sufficiently for the wire to slip past them, but when the strain ceases, the serrated faces of the dogs G I have gripping engagement with the wire to preclude any retrograde movement thereof, whereby the looped wire is held under tension by the gripping action of the dogs G I. These dogs hold the loop under tension independently of the rockers J, K, and the tension means. The lever L is now moved rearwardly to the idle position shown in Figures 1, 2 and 3, which movement turns the rockers J, K, in a direction reversed to their movement when tensioning the wire, and at this time the wire adjacent the deformed part y slips idly through the gripper M, see Figure 9, and that part of the wire wrapped on the stud n is slackened up to the dog I, whereby the return to normal of the tension means renders the lever L available for applying pressure on the machine for holding it steadily in place during the succeeding operations of twisting the wire and of cutting surplus material from the ends of the loop. At this stage of the operation, the wire composing the loop is held by the dogs G I under tension around the package, see Figure 8. Both levers L P being rearwardly of the twister, the operator presses downward with one hand on lever L, and pulls upwardly and forwardly on lever P with the other hand, thereby rotating the gear segment and the twister pinion, the effect of which is to inter-twist the parallel parts y' , y^2 , of the wire, said parallel wire parts being held from rotative movement around each other by the walls of the slots in plates D E. The twists having been completed by the rotation of the twister to its required position, the studs r of the gear segment are in contact with the upper ends of the knives Q, R, and by applying pressure to the lever P the gear segment is turned a certain angular distance so as to forcibly actuate the cutters and sever the respective parallel parts y' y^2 adjacent the twists, cutting surplus wire from the completed loop while allowing such surplus wire to remain attached to the gripper M and stud n of the rockers J, K.

After cutting surplus wire from the ends of the loop, the pressure is relaxed on lever P, whereupon the spring-actuated knives Q R act to raise lever P slightly, thereby returning the slotted pinion C to an open position, and the machine is then shoved bodily in a rearward direction by pushing on the lever P, thus displacing the machine from the loop, the twisted portion slipping out of the slotted pinion, and the throat of the machine, the loop remaining in place on the package. One severed part of the wire cut from the loop is pulled through the gripper M and dog G, whereas the other severed part

of the wire is detached from the stud and pulled out of dog I, these operations being easily performed to place the machine in condition for a subsequent operation.

In order to reduce the frictional contact between the wire band and the directing members F H, it is permissible to use frictional rolls where the band of the wire is made around the curved faces $f h$, it being apparent that two friction rolls may be substituted for the curved faces $f h$ of members F H at the places where the wire bends in order to lead said wire from the throat of the machine to the gripping devices on the rockers J K of the tension device.

Having thus fully described the invention, what I claim as new and desire to secure by Letters Patent is:

1. In a package banding machine, tension means including a plurality of members turnable on an axis substantially parallel to the plane of a looped band, said members being provided with means for the attachment of the respective end portions of said looped band, means for turning said members concurrently whereby the members co-operate for tensioning said band, and band-holding means separate from said turnable members and engageable with said looped band for retaining said band under tension.

2. In a package banding machine, tension means including a plurality of pulling members turnable on an axis substantially parallel to the plane of a looped band, and means for turning said members whereby the looped band is tensioned, in combination with a plurality of band-holding dogs engageable independently of the pulling members with said looped band for holding said band under tension.

3. In a package banding machine, band tensioning means including a plurality of rockers each provided with a band holder, said rockers being rotatable on an axis substantially parallel to the plane of a looped band.

4. In a package banding machine, means for positioning a looped band in a predetermined plane, and tensioning means including a plurality of rockers rotatable on an axis substantially parallel to the plane of said looped band.

5. In a package banding machine, tension means including a shaft, and a plurality of heads carried by said shaft and rotatable therewith, in combination with means for positioning a looped band, the terminal portions of which are attached to the respective heads.

6. In a package banding machine, tension means including a plurality of rockers, in combination with means for positioning a looped band, and directing means for the terminal portions of said looped band, whereby said terminal portions are turned

out of the plane of the loop and positioned for attachment to the respective rockers.

7. In a package banding machine, tension means including a single shaft and a plurality of rockers carried by said shaft and rotatable therewith, in combination with means for positioning a looped band for the terminal portions thereof to be engaged by said rockers.

10 8. In a package banding machine, band-tensioning means including a single shaft, a plurality of rockers carried by said shaft, each rocker being provided with a curved surface with which a terminal portion of a 15 looped band is adapted to contact, and band-attaching means movable with each rocker.

9. In a package banding machine, band-tensioning means including a single shaft, a rocker carried by said shaft, an automatic 20 band-gripper movable with said rocker, a second rocker also carried by the shaft, and a separate band fastener movable with the second rocker.

10. In a package banding machine, band-tensioning means embodying a plurality of 25 members rotatable on an axis substantially parallel to the plane of a looped band and operable concurrently for tensioning said looped band by applying strain to the respective end portions of said band, one of 30 said rotatable members being provided with means engageable with a cross-sectionally deformed portion of a preformed band.

11. In a package banding machine, band-tensioning means embodying a plurality of 35 members rotatable on an axis common to both members and operable concurrently for tensioning a looped band by strain applied to the end portions of said band, and a 40 gripper carried by one of said tension members and movable relatively thereto for engagement automatically with a band, said gripper and tension head being co-operable for engagement with a cross sectionally de- 45 formed part of a preformed band.

12. In a package banding machine, band-tensioning means including a plurality of 50 rockers operable concurrently for pulling the respective end portions of a looped band, and a band-gripper carried by one of said 55 rockers, in combination with band-guiding means positioned in co-operative relation to each of said rockers for directing the end portions of said looped band relatively to said rockers.

13. In a package banding machine, band-tensioning means including a plurality of 60 rockers, one of which is provided with an automatic band-gripper, and said rockers being operable concurrently for pulling the respective end portions of a looped band, in combination with a plurality of band-guiding devices positioned in co-operative relation to said rockers, one of said band-guid-

ing devices being related to one rocker and 65 to the band-gripper thereon that an end portion of said band is initially directed into position for the engagement automatically therewith of said band-gripper.

14. In a package banding machine, band-tensioning means including a plurality of 70 rockers operable concurrently for pulling the respective end portions of a looped band, and a band-gripper carried by one of said 75 rockers and operable for engagement automatically with an end portion of the band when the latter is introduced initially to said rocker and the band-gripper, in combination with means for directing the end portions of said looped band relatively 80 to the rockers.

15. In a package banding machine, band-tensioning means including a single shaft, and a plurality of rockers spaced relatively 85 to each other on said shaft and turnable therewith in pulling the respective end portions of a looped band for placing the latter under tension.

16. In a package banding machine, band-tensioning means including a continuous 90 shaft and a plurality of rockers spaced relatively to each other on said shaft and rotatable therewith, said rockers being adapted for the attachment of the respective terminal 95 portions of a band, in combination with band-directing members each positioned in operative relation to one of said rockers, and band-gripping members separate from the rockers and acting independently of said tension means to preclude relaxation of the 100 tension applied to said band.

17. In a package banding machine, band-tensioning means including a rotatable part, and a plurality of band-gripping dogs pivot- 105 ed to said rotatable part and movable therewith in applying tension to a band, said dogs in the at rest position of the rotatable part being movable relatively to each other for the introduction therebetween of a band and said dogs being actuated for engagement normally with said band during the rotative movement of said rotatable part.

18. In a package banding machine, band-tensioning means including a rocker and a band-gripper carried by said rocker, said 115 band-gripper embodying a plurality of dogs co-operable with a preformed shouldered band, one of which is movable relatively to the other and both of which are engageable with a band adapted to be inserted between said dogs.

19. In a package banding machine, band-tensioning means including a rocker and a band-gripper carried by said rocker, said 125 band-gripper embodying a plurality of dogs, one of which is fixed and the other of which is spring actuated for movement relatively to the fixed dog, said dogs being relatively

positioned to facilitate the introduction of a band and said dogs being engageable frictionally with said band.

20. In a package banding machine, tensioning means including a plurality of rockers, each provided with means for the attachment of an end portion of a looped band, of a plurality of dogs engageable with said end portions of the band, one of said dogs being movable on a vertical axis and the other dog movable on a horizontal axis and both of said dogs being independent of the tension means for holding the band under tension when said tension means is moved into and out of service position.
21. Tension means for a package banding machine embodying a plurality of members rotatable on an axis substantially parallel to the plane of a looped band, means for

imparting rotative movement to said tension members, and band directing means for deflecting the respective band ends at an angle to the plane of said loop of the band.

22. Tension means for a package banding machine embodying a plurality of tension members rotatable on an axis substantially parallel to the plane of a loop in a band, means for directing the respective ends of said band in a direction substantially at a right angle to the plane of said loop, and means for concurrently actuating said tension members, whereby the loop is tensioned by applying strain to the respective ends of said band.

In testimony whereof I have hereto signed my name this 13th day of May, 1924.

CHARLES S. WEEKS.
